Primary Examiner — Paula Allen Greene

(57) **CLAIM**

The ornamental design for a headphone stand, as shown and described.

DESCRIPTION

FIG. 1 is a front, right, and top perspective view of a headphone stand, showing my new design;
FIG. 2 is a rear, left and bottom perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an enlarged view of the portion labeled "9" framed in FIG. 1.

The broken lines shown in the drawings depict portions of the headphone stand that form no part of the claimed design. The dot dash broken lines encircling portions of the headphone stand in FIG. 1 and illustrated in the enlarged view of FIG. 9 form no part of the claimed design.

1 Claim, 9 Drawing Sheets
